UNITED STATES PATENT OFFICE.

FRANCIS I. DU PONT, OF WILMINGTON, DELAWARE, ASSIGNOR TO DELAWARE CHEMICAL ENGINEERING COMPANY, OF WILMINGTON, DELAWARE, A CORPORATION OF DELAWARE.

LIQUID-VENDING MACHINE.

Application filed July 6, 1922. Serial No. 573,117.

To all whom it may concern:

Be it known that I, FRANCIS I. DU PONT, a citizen of the United States, residing at Wilmington, county of New Castle, and State of Delaware, have invented a new and useful Improvement in Liquid-Vending Machines, of which the following is a full, clear, and exact description, reference being had to the accompanying drawings, which 10 form a part of this specification.

This invention relates to an improvement in coin-controlled liquid vending machines, and more particularly to machines for dispensing gasoline, oils, etc.

15 I am aware that coin-controlled liquid vending machines are old in the art, but in all such machines known to me the machines are designed to deliver a fixed quantity or quantities.

20 The object of my invention is to provide a machine of this character which, while adapted to deliver a predetermined volume of liquid for each coin of a fixed denomination that may be inserted, is so adjustable that the predetermined volume deliverable upon the insertion of a coin may be varied in accordance with variations in the customary retail market price of the liquid, that is, may be increased as the market price falls or decreases as the market price rises. For example, if a machine for vending gasoline is designed to receive half dollars, it should have a maximum capacity of (say) three gallons, and when so designed 25 it would be adjustable to deliver the proper amount of gasoline for a half dollar so long as the price does not fall below seventeen cents per gallon. If the price of gasoline is seventeen cents per gallon, the device would be adjusted to deliver 2.94 gallons for each half dollar inserted. If the price is twenty cents, 2.5 gallons will be delivered, and if the price is twenty-eight cents, 1.8 gallons 30 will be delivered.

45 The device is preferably provided with a scale indicating prices, together with an adjustable pointer connected to the measuring device, and so arranged that when adjustments are made, both the measuring mechanism and indicator are simultaneously 50 adjusted.

In the specific form shown, this is accomplished by means of a bucket having a

greater capacity than the maximum delivery to be made and a fluid displacer of calculated volume. The bucket is raised to a pre-determined position with relation to the displacer, and all of the fluid displaced in the bucket by the displacer flows to a delivery pipe through which it passes to the point of 55 delivery.

The device is so arranged that the depth to which the displacer is moved into the liquid when the bucket is moved to its delivery position may be readily adjusted so 60 that the quantity of gasoline delivered for the coins can readily be varied in accordance with the price.

The precise nature of my invention will be best understood by reference to the accompanying drawings, which will now be described, it being premised, however, that changes may be made in the form and construction of the device without departing from the spirit and scope of my invention 75 as defined in the appended claims.

Fig. 1 is a side elevation, partially in section, somewhat diagrammatic, which shows one form of apparatus constructed in accordance with my invention.

Fig. 2 is a detail side elevation of the mechanism for receiving the fluid from the bucket.

Fig. 3 is a vertical section through the bucket filling pipe.

Fig. 4 is a detail sectional view showing the clutch mechanism and the coin-controlled means therefor.

Fig. 5 is a detail sectional view of Fig. 4, showing the coin delivery chute in connection with the levers.

Fig. 6 is a sectional plan view of a portion of Fig. 1, showing the relation of the bucket and weight in the filling pipe.

Figs. 7 and 8 are side elevations of the 95 bucket in different positions.

Fig. 9 is a perspective view of certain parts of the apparatus.

In these drawings, the reference character 2 designates a gasoline tank and 3 a filling 100 connection therefor. 4 is a vertical pipe which extends below and above the tank 2 and is connected thereto by tubes 5 so that the gasoline will freely flow from the tank 2 to the pipe 4. Mounted on the top of the 105 pipe 4 is a casing 6 in which is housed the

mechanism for actuating the bucket for delivering the gasoline.

- Connected to support 7 on the bottom of pipe 4 and similar supports 8 connected to the casing 6 or a suitable frame therein are two guide rods 9. 10 is a bucket which is provided with ears 11 which slidably engage the rods 9. This bucket 10 is provided with a spout 12 at about the center thereof.
- 10 Mounted in suitable bearings in the frame or supported by the casing is a shaft 13, having connected thereto two sprocket wheels 14 and 15. 16 is a sprocket chain which passes over sprocket wheel 14. 17 is a weight connected to one end of the chain 16, the other end of the chain being connected to the upper ear 11 on the bucket at the side opposite that shown in Fig. 1. The weight of the bucket 10 when filled is somewhat less than that of weight 17 so that the filled bucket will be elevated to its discharging position by the weight as hereinafter described. 18 is a displacer which is supported by a frame or yoke 19 which is mounted for adjustment along rods 9. This displacer is so positioned that when the bucket is elevated to its extreme position by the weight 17, the displacer will be within the bucket 10.
- The yoke 19 is provided with a rack 20 which is engaged by a pinion 21 on a shaft 22, journaled in suitable bearings in the frame. 23 is a drum on shaft 22 and 24 is a cable or chain, the one end of which is connected to the drum while the other end thereof is connected to a sliding nut 25. This nut 25 is held against rotation by means of guides 26 within a casing 27, supported on the bottom of casing 6. One of the guides is graduated and may be numbered to indicate different prices, say 17 to 35.
- The nut 25 is engaged by a screw rod 28, which is rotatably mounted in casing 27, and which rod is held against vertical movement by its bearings.
- 45 The displacer 18 is shown positioned at its lowest point so that the device as now set will deliver the maximum amount of gasoline.
- The attendant adjusts the nut 25 by the screw 28 to place the pointer extending from the nut in the plane of the mark indicating the price of gasoline. This adjustment of the nut will position the displacer 18 at the proper point to deliver the proper amount of gasoline for the coin received, at the price indicated by the pointer.
- The casing 27 is closed by a door having a glass panel through which the purchaser can see the price charged per gallon, and the door is also provided with a lock to prevent unauthorized persons tampering with the adjustment of the displacer.
- The bucket 10 is normally in its elevated position and is held in such position by the weight 17, which is then in the lower part of
- the pipe 4. The weight is raised and controlled by mechanism within a casing 30 and comprises a shaft 31 rotatably mounted in bearings 32 on the casing and at one end of the shaft. The other end of the shaft is 70 rotatably mounted in a sleeve 33 which is in turn rotatably mounted in a bearing in the casing and is maintained against longitudinal movement by said bearing. The shaft 31 is maintained against longitudinal movement by a collar 34 which is secured to the shaft between bearings 32. Connected to shaft 31 is a sprocket wheel 35, which is connected to sprocket wheel 15 on shaft 13 by a sprocket chain 36. Connected to sleeve 33 80 is a crank 37, a clutch member 38 and a ratchet wheel 39. 40 is a pawl arranged to prevent the ratchet wheel and crank from rotating counter-clockwise. Splined to shaft 31 so as to rotate therewith and at the same time permit longitudinal movement thereon is a clutch member 41. Pivotally mounted at 42 in a fork 43 extending from one side of the casing 30 is a clutch actuating lever 44, having an arcuate U-shaped arm 45 for 90 the purpose hereinafter described. 46 is a spring-actuated plunger connected to lever 44 for retaining the clutch member 41 in either of its extreme positions.
- Clutch lever 44 is provided with an arm 44^a which is connected by means of a link 47 with one arm of a bell crank 48, pivotally mounted in pipe 4. The other arm of this bell crank is in the path of a projection 49 on chain 16.
- Pivotally mounted at 42 above lever 44 is a control lever 50 which is maintained in the position shown in Fig. 4 by a spring 51. This lever 50 is also provided with an arcuate extension 52 between the legs of extension 45 of clutch lever 44. Both of these extensions are provided with coin slots and are in alignment with each other when the parts are in the positions shown in Figs. 4 and 5, and 53 is a coin chute leading from a coin slot 54 in casing 30 to the coin slots in the levers when the levers 44 and 50 are in their normal positions shown in Figs. 4 and 5.
- The gasoline is discharged from the 115 bucket 10 through spout 12 when the bucket is raised by the weight to enclose and submerge the displacer, and the gasoline which flows out through the spout is delivered to a suitable pipe by the following mechanism.
- Connected to a pipe 55 is a frame 56, which frame has a boss 57 slidably mounted on one of the rods 9. The upper end of pipe 55 is slidably mounted in a projection 58 extending from a casing 6 or a frame therein, 125 while the lower end of the pipe telescopically engages a pipe 59. 60 is a gasoline delivery pipe extending from pipe 59 through which the gasoline is delivered to the purchaser and may be provided with any form of nozzle 130

and flexible connection. The pipe 55 is provided with a T 61 to which a rotatably connected one end of a pipe 62, the other end thereof being closed and is provided with a lever 63. This latter end is rotatably supported in a bracket 64 secured to pipe 55 and forms a stop for said pipe, which engages the top of pipe 59 when the frame 56 and its parts are in their lowered positions. Connected to pipe 62 and communicating therewith is a funnel 65 which is arranged to be swung below spout 12 when the bucket 10 is raised and to be moved from under the spout when the bucket is lowered.

Pivotaly connected to frame 56 is a bell crank 66, one arm of which is connected to lever 63 by a link 67. The other arm of this bell crank 66 is in the path of a pin 68 on the upper ear 11 of the bucket at the side opposite the chain 16. 68^a (Fig. 1) is a spring connected to frame 56 and bell crank 66 and which holds the various levers and funnel 65 in the position shown, clear of spout 12, when the parts are in their lowered positions.

The weight 17 is pointed so as to readily enter the gasoline in pipe 4 without splashing. The lower end of displacer 18 is also pointed to readily enter the gasoline in the bucket and gradually reduce the speed of movement thereof, which acts as a dash pot plunger during the final upward movement of the bucket.

The parts when in their normal positions are in the positions shown in Figs. 1, 4 and 5 with the exception that the bucket and frame 56 are in their elevated positions and the weight is in its lowered position.

The purchaser deposits the coin in slot 54, which is delivered to the slots in levers 44 and 50 and will lock the levers to each other. Lever 50 is then moved to the left, which will in turn shift the clutch lever 44 in a direction to move clutch member 41 toward member 38. Immediately after clutch lever 44 has passed its central position, spring plunger 46 will shift said lever and member 41 to clutching position. This movement of the clutch lever will carry the coin free of lever 50 as the front part of its slot is cut away, and carry the coin over slot 71 in the top of a coin receptacle in casing 30, into which it will fall. The operator now releases lever 50 which will be re-

turned by its spring 51 and position the slot in said lever under chute 53. The extension 45, however, of lever 44, which straddles lever 50, will prevent a coin passing from chute 53 until the clutch lever 44 is again in the position shown in Fig. 4. The operator now turns the crank 37 in a clockwise direction until the bucket 10 has been lowered into pipe 4 and the weight 17 has been raised, as shown in Fig. 1. During the rotation of the crank 37, the bucket 10 will

fall as rapidly as the weight 17 is raised until the bucket contacts with the gasoline which will slow up the movement of the bucket unless the crank is turned very slowly. As the weight of the bucket is greater than that of the gasoline displaced by that portion of the bucket below the lower edge of the inlet to spout 12, the bucket will sink slowly until the spout is submerged. As the spout is relatively large, the bucket will fill rapidly therethrough and sink to the position shown in Fig. 1. Just before the bucket reaches the point shown in Fig. 1, projection 49 on chain 16 will trip lever 48, which in turn through the link 47 and lever 46 will shift clutch lever 44 and disengage the clutch members. This disengagement of the clutch members, as will be seen by reference to Fig. 9, will release the weight 17 through the release of sprocket 35, which will fall and raise the bucket to its extreme upper position, where it will be retained by the weight until the crank is turned after insertion of the next coin. During the upward movement of the bucket, the surplus gasoline above spout 12 will fall back into the pipe 4 before the bucket reaches the end of such pipe. As the bucket rises, pin 68 on one of the ears 11 will engage the horizontal arm of bell crank 66 and said ear 11 will then engage boss 57 on frame 56. The engagement of bell crank 66 by pin 68 will shift the funnel 65 under spout 12, as shown in Fig. 7, just as the point of displacer 18 is about to enter the gasoline in the bucket, when adjusted to deliver the maximum amount of gasoline which can be delivered by the device.

As the bucket raises from the position shown in Fig. 7, the frame 56 together with the various parts connected thereto will be carried upwardly with the bucket until the upper ear 11 to which claim 16 is connected, engages the boss 8 above it. If the speed of the rise of the bucket is such as to cause the displacer 18 to displace the gasoline more rapidly than it will flow through the spout 12, the gasoline will rise above the spout, but in no event will the displaced gasoline flow over the top of the bucket as the capacity of the bucket above the spout is greater than the volume of the displacer 18.

When the bucket is lowered for the next charge, the frame 56 and all of the elements carried thereby will fall until bracket 64 engages pipe 59, and as pin 68 moves from under bell crank 66 spring 68^a will shift funnel 65 from under spout 12.

The advantages of my invention result from the provision of a coin-controlled liquid vending machine having means for positively varying the quantity delivery capacity to any degree below the maximum delivery capacity, whereby the quantity de-

livered for the coin received may readily relative to the container when in its dis- 65
be varied as the price of the liquid being
dispensed varies.

Having now fully described my invention, what I claim and desire to protect by Letters Patent is:

1. A liquid dispensing device having measuring means, comprising a liquid container and liquid displacer, said container 10 having an outlet above the bottom thereof and of sufficient capacity below the outlet to hold a greater quantity of liquid than is dispensed at any one time, means for filling the container for each dispensing operation, 15 and means for moving the container and displacer relative to each other during each dispensing operation, to cause the displacer to enter the container and force a predetermined quantity of liquid from the 20 container through the outlet.

2. A liquid dispensing device having measuring means, comprising a liquid container and liquid displacer, said container having an outlet above the bottom thereof 25 and of sufficient capacity below the outlet to hold a greater quantity of liquid than is dispensed at any one time, means for filling the container for each dispensing operation, means for moving the container 30 and displacer relative to each other during each dispensing operation, to cause the displacer to enter the container and force a predetermined quantity of liquid from the container through the outlet, and means for 35 varying the depth to which the displacer is moved into the container, to vary the dispensing capacity of the measuring means.

3. A liquid dispensing device having measuring means, comprising a liquid container 40 and a liquid displacer, there being an outlet from the container above the bottom thereof, the volume of the liquid capable of being held by the container being greater than the volume of the displacer 45 and means for moving the container into filling and discharging positions, said displacer being arranged to be positioned in the container to force liquid from the container through the outlet when the container 50 is moved into discharging position.

4. A liquid dispensing device having measuring means, comprising a liquid container and a liquid displacer, there being an outlet from the container above the bottom thereof, the volume of the liquid 55 capable of being held by the container being greater than the volume of the displacer, means for moving the container into filling and discharging positions, said displacer 60 being arranged to be positioned in the container to force liquid from the container through the outlet when the container is moved into discharging position, and means for adjusting the position of the displacer

5. A liquid dispensing device comprising a liquid reservoir, a liquid receiver, a bucket movable into and out of said reservoir, a displacer adapted to enter said bucket and thereby displace liquid therefrom into the receiver, means to operate the bucket, coin-controlled mechanism for releasing said means, and adjustable mechanism for varying the amount of fluid displaced by the 75 displacer.

6. A liquid dispensing device having a liquid elevating container, mechanism for lowering the container into filling position and to elevate it into emptying position, 80 coin-controlled mechanism for controlling the movement of the lowering and elevating mechanism, means for discharging the liquid from the container when elevated, and means for adjusting the discharging 85 means to vary the discharge to any degree below the maximum capacity of the dispensing device.

7. A liquid dispensing device having a bucket for raising the liquid from a well to 90 a point from which it will flow by gravity, a weight for raising the bucket, weight-raising mechanism, a crank for actuating the weight-raising mechanism, coin-controlled mechanism for connecting the crank and 95 weight-raising mechanism to each other, a displacer for forcing the liquid to be dispensed from the bucket, and means for adjusting the displacer to vary the quantity 100 of liquid displaced to vary the quantity delivered for the coin received in accordance with the variation in the price of the liquid being dispensed.

8. A liquid dispensing device having a bucket for raising the liquid from a well to 105 a point from which it will flow by gravity, a liquid-receiving device for receiving the liquid from the bucket, a weight for raising the bucket, mechanism for shifting the bucket and liquid-receiving device into proper relation to each other to permit liquid to flow from one to the other, means controlled by the bucket for actuating said last mentioned mechanism, weight-raising mechanism, a 110 crank for actuating the weight-raising mechanism, coin-controlled mechanism for connecting the crank and weight-raising mechanism to each other, a displacer for forcing the liquid to be dispensed from the bucket, and means for adjusting the displacer to 115 vary the quantity of liquid displaced to vary the quantity delivered for the coin received in accordance with the variation in the price of the liquid being dispensed.

In testimony of which invention, I have 120 hereunto set my hand, at Wilmington, Delaware, on this 1st day of July, 1922.

FRANCIS I. DU PONT.
